UNITED STATES PATENT OFFICE.

HENRY M. SHEER, OF QUINCY, ILLINOIS.

DESIGN FOR AN INCUBATOR.

45,434.

Specification for Design.

Patented Mar. 17, 1914.

Application filed December 2, 1913. Serial No. 804,325. Term of patent 14 years.

To all whom it may concern:

Be it known that I, HENRY M. SHEER, a citizen of the United States, residing at Quincy, in the county of Adams and State of Illinois, have invented a new, original, and ornamental Design for Incubators, of which the following is a specification, reference being had to the accompanying drawing, forming part thereof.

The accompanying drawing is a view in perspective of the incubator.

I claim:

The ornamental design for an incubator, as shown.

HENRY M. SHEER.

Witnesses:

GERHARD G. ARENDTS,
HENRY DAMHORST.
